UNITED STATES PATENT OFFICE

2,436,633

THERMOSTATIC SWITCH FOR CONTROL-
LING ELECTRIC CIRCUITSThomas Curzon, Acton, London, England, assignor
to C. A. V. Limited, London, EnglandApplication November 13, 1944, Serial No. 563,239
In Great Britain October 1, 1943

4 Claims. (Cl. 200—88)

1

This invention relates to thermostatic protective switches, for use in electricity distributing systems, and has for its object to provide improved switches of the kind adapted to open in the event of a fault or other condition causing an abnormal current to flow in a circuit containing the switch, and also adapted to be prevented from automatically reclosing.

In the accompanying sheet of explanatory drawings,

Figure 1 is a sectional side view of a switch mechanism embodying the invention, and Figure 2 is a diagram illustrating the electrical connections of the switch mechanism.

In carrying the invention into effect as shown an electromagnet *d* is secured in any convenient manner to a supporting plate *n* having a central aperture, and is enclosed by a sheet metal or other casing *m* having an open end secured to the supporting plate, the other end of the casing being closed. The electromagnet *d* comprises a yoke *o*, a winding *e*, and a spring loaded armature *f*, the latter having one end hingedly attached by a resilient metal strip *p* to the inner end of the yoke, and having a contact *a* on its other end. At a position adjacent to the armature *f* there is arranged within the casing *m* a bi-metal strip *c* which at one end is secured to a metal piece *q*, the other end of the bi-metal strip having mounted on it a contact *b* adapted to co-operate with the contact *a*. The ends of the electromagnet winding *e* are electrically connected to the metal piece *q* and the electromagnet yoke *o* respectively. The metal piece *q* is situated in part between and electrically insulated from one side of the electromagnet yoke *o* and a second metal piece *r*, the latter being secured and electrically connected to the said yoke by screws *s* which also serve to secure the first-mentioned metal piece in position. A third metal piece *t* is secured by screws *u* to the other side of the electromagnet yoke *o*, but is electrically insulated therefrom in any convenient manner. The second and third metal pieces *r*, *t* extend through the closed end of the casing *m*, and are provided at their outer ends with terminal screws *v* for connection to the circuit to be controlled.

For electrically interconnecting the first and third metal pieces *q*, *t*, I employ a push-pull switch *i* having a pair of fixed contacts *w* and a pair of complementary movable contacts *x*. The fixed contacts *w* are respectively secured to the metal pieces *q*, *t* at positions near the supporting plate *n*, and are formed at their adjacent sides with V-shaped recesses *y* for accommodating

2

complementary parts of the movable contacts *x*. The latter are interconnected by a resilient metal bridge piece *z*, and are operable by an axially movable stem *2* which passes through the central aperture in the supporting plate *n* and is provided at its outer end with a finger piece *3* made from insulating material. The finger piece *3* is formed with a tubular extension *4* which is slidable in a fixed tubular guide *5* on the supporting plate *n*.
10 The stem *2* passes through a central hole in the bridge piece *z* and is surrounded by a pair of helical compression springs *6* through which movement can be imparted by the stem to the bridge piece for actuating the movable contacts
15 *x*, one of the springs being situated between the bridge piece and the finger piece *3*, and the other being situated between the bridge piece and a head *7* on the inner end of the stem. Secured to the supporting plate *n* and situated between
20 the latter and the fixed contacts *w* are a pair of insulating pieces *8* which at their adjacent sides are also formed with V-shaped recesses *9* for accommodating the movable contacts *x*.

The contacts *a*, *b*, are normally closed, and
25 when in this condition they short-circuit the electromagnet winding *e* which is of relatively high resistance. Assuming that the main switch *i* is closed and that the metal pieces *r*, *t*, are connected to the circuit to be controlled, the contacts *a*, *b* remain closed so long as normal conditions exist in the said circuit, but in the event of a short-circuit or other condition causing abnormal heating of the strip *c* the said contacts are separated, whereupon current flows through
30 the winding *e* and excites the electromagnet *d*. This causes rapid and complete separation of the contacts *a*, *b* and prevents reclosure thereof in consequence of the strip *c* cooling. When removing the fault the main switch *i* is opened. The
35 electromagnet *d* then ceases to act, and the cooled strip *c* allows the contacts *a*, *b*, to come together again.

When the switch *i* is closed its movable contacts *x* engage the recesses *y* in the fixed contacts *w*. To open this switch a pull is exerted on the finger piece *3*. The effect of this is to compress the spring *6* arranged between the bridge piece *z* and the head *7* of the stem *2* until this spring causes the movable contacts *x* to be
45 disengaged from the recesses *y* in the fixed contacts *w* and moved into engagement with the recesses *9* in the insulating pieces *8*. Reclosure of the switch *i* is effected by exerting a push on the finger piece *3*. This causes the other spring
50 *6* to be compressed until it causes the movable
55 contacts *x* to be disengaged from the recesses *9* in the insulating pieces *8*. Reclosure of the switch *i* is effected by exerting a push on the finger piece *3*. This causes the other spring

contacts *x* to be disengaged from the recesses *y* and re-engaged with the recesses *y*. It will be seen therefore that both the opening and closing movements of the contacts *x* are effected rapidly under spring action.

If desired the position of the contact *b* may be adjusted by a set screw *10* carried by the metal piece *q* and acting on the bi-metal strip *c*.

Whilst I prefer to employ bi-metal strip for the separation of the normally closed contacts on account of its simplicity and convenience, I may in some cases employ any other convenient thermally deformable means for separating the contacts.

Having thus described my invention what I claim as new and desire to secure by Letters Patent is:

1. A thermostatic switch of the kind specified, having in combination a pair of normally closed and independently movable contacts, a heat responsive device, and an electromagnet having its winding permanently connected across said contacts, one of said contacts being movable by said heat responsive device to cause separation of said contacts and the other contact being arranged to be attracted and actuated by said electromagnet, so that in the event of separation of said contacts by said heat responsive device said contacts are held apart by said electromagnet.

2. A thermostatic switch as claimed in claim 1, in which the normally closed and independently movable contacts are respectively carried by a bi-metal strip forming the heat responsive device and by an armature forming a part of the electromagnet.

3. A thermostatic switch as claimed in claim 1

and having in an electric circuit containing the normally closed and independently movable contacts, a controlling push-pull switch, the two switches being formed as a unitary structure.

4. A thermostatic switch as claimed in claim 1 and having in an electric circuit containing the normally closed and independently movable contacts, a controlling push-pull switch comprising in combination a pair of fixed contacts, a pair of resiliently interconnected movable contacts adapted to co-operate with said fixed contacts, an operating member and springs through which movement can be imparted to said resiliently interconnected movable contacts under the action of said operating member, the two switches being formed as a unitary structure.

THOMAS CURZON.
